UNITED STATES PATENT OFFICE

JOHANN NOVOTNY, OF KARLSBAD, CZECHOSLOVAKIA

DEVICE FOR ATTACHING SAVING MEANS TO SUNKEN SUBMARINES

Application filed April 26, 1930. Serial No. 447,656.

My invention relates to improvements in devices for attaching saving means to sunken submarines, the main object being to provide a device which is in permanent connection with the deck of a submarine and to which saving means of different kind may be attached in the case of the submarine being sunk, the said means being intended for allowing the crew of the sunken boat to communicate with a ship sent out for help.

My invention will be more fully understood by reference to the accompanying drawings forming a part of this specification, and in which:

Fig. 1 is a perpendicular section through the device in connection with the deck of a submarine,

Fig. 2 is a side elevation of the mounted device,

Fig. 3 is a horizontal cross-section upon the line 3—3 of Figure 1, and

Fig. 4 shows a detail view, in a section and in a plan view respectively.

Describing a convenient form of the invention such as I wish it to be applied to the deck of a submarine, the device comprises a main piece *a*, preferably made of steel and made in the shape of a cylinder, the outer face thereof carrying a screw-thread *b* intended for being screwed into a screw-threaded opening provided in the boat's deck *c*, the said opening being positioned so as to establish a communication with the room for the crew. The inner face of the said cylinder is also provided

with a screw-thread designated by *d* and adapted to be screwed into engagement with the externally threaded portion of a cylindrically shaped member *e* made substantially of steel and the upper edge of which over-

topping the edge of the cylinder *a*. In the said cylinder *e* there are vertically mounted three steel tubes *f*, *g* and *h* positioned at equal distance from each other and projecting at their top from the circular wall of the said cylinder.

The tubes *f* and *g* are at their top and lower ends each provided with an external screw-thread *i* and *k*, and *l* and *m* respectively, and these tubes together with the lower extremity of the tube *h*, are projecting from the lower circular wall of the cylinder

All the said tubes are normally closed by valves (not shown in the drawings) to be operated by hand, and both screw-threaded ends of the tubes *f* and *g* are each adapted to be brought in connection with flexible tubes, the one for introducing fresh air into the submarine and the other for expelling the bad air; the third tube *h* serves for the introduction of a telephone cable having an envelope of rubber or of any other suitable insulating and protecting material.

The described arrangement may be closed at top and foot by two covers *n* and *o* respectively. To this end, the upper half of the cylinder *e* is provided with an external screw-thread *p*, and the lower half of the said cover *n* is provided with an internal screw-thread *q*; and the lower portion body of the cylinder *a* is provided with an internal screw-thread *r*, whereas the cover *o* having its top portion made in the shape of a turned-in flange *o*¹, carries at the outer face of the said flange a screw-thread *s*. Both covers, shown in their operative or closing position in Figure 1, are each terminated by a hexagonal head *t* and *u* respectively, to be operated by means of a suitable wrench.

In operation: When, owing to an accident, a submarine sinks, it discharges in known manner oil which, rising to the surface of the water, indicates the place where it is positioned on the sea ground. The ship sent out to bring help, easily finds this place, and causes its diver to descend to the sunken boat.

As soon as the diver has reached the deck of the boat, he is looking for the emplacement of the described device (the upper half of which projecting from the level of the deck), and having found the said emplacement, he is knocking at the deck in order to have the crew informed of the help brought, and the crew has to answer by knocking likewise. Now, the diver unscrews the cover *n* from its seat by means of a wrench, the said cover being preferably in connection with an attaching chain so as to prevent its loss. After having unscrewed the cover, the diver introduces into the open-ended tube *h* the extremity of a telephone cable taken with him. In the meantime, the crew, inside the sunken

boat, has removed the cover *o* from its seat, opened the valve and drawn the said telephone cable into the interior of the submarine. Thus, the crew is enabled to communicate with the saving ship. Now, the 5 diver has screwed in position upon the screw-threaded ends *i*, *k* of the tubes *f* and *g* respectively, a flexible tube for introducing fresh air into the submarine, and a flexible 10 tube for having the bad air expelled therefrom, the valves of the said tubes having been opened by the crew and a flexible tube having been likewise screwed in position upon the screw-threaded inner extremities *l* and *m* of 15 each tube *f* and *g* respectively. The crew is thus prevented from perishing by the action of stale air.

While the elements shown and described are well adapted to serve the purposes for 20 which they are intended, it is to be understood that the invention is not limited to the precise construction set forth, but includes within its purview such changes as may be made within the scope of the appended 25 claims.

Having described my invention, what I claim is:

1. A device for attaching saving means to sunken submarines of the character described, comprising in combination, a cylinder made of steel, having an external screw-thread adapted to be screwed in position into an internal screw-threaded passage made in the deck of the submarine to communicate 30 with the crew's room; and having an internal screw-thread for engagement with the external screw-thread of a cylindrically shaped member positioned inside the said cylinder, a series of tubes mounted in the cylindrically shaped member, the said tubes being intended for the reception of saving 35 means, and covers for removably closing top and bottom of the said cylinder.

2. A device for attaching saving means to sunken submarines of the character described, comprising in combination, a cylinder made of steel, having an external screw-thread adapted to be screwed in position into an internal screw-threaded passage made in the 45 deck of the submarine to communicate with the crew's room; and having an internal screw-thread for engagement with the external screw-thread of a cylindrically shaped member positioned inside the said cylinder, a series of tubes mounted in the cylindrically shaped member, two of the said tubes being 50 at their top and bottom each provided with an external screw-thread adapted to be brought in connection with flexible tubes for introducing fresh air into the boat's room and for expelling bad air therefrom, the 55 third tube being adapted for the reception of a telephone cable, an external screw-thread at the outside of the cylindrically shaped innermost member intended for being screwed 60

together with a cover removably closing the top of the device, and an internally arranged screw-thread at the lower portion of the main cylinder adapted for being screwed together with a cover removably closing the bottom of the device. 70

In testimony whereof I have affixed my signature.

JOHANN NOVOTNY.
